ELECTRICAL CONDUCTOR SUPPORT

Paul E. Lewis, Mexico, and Robert W. Harmon, Centralia, Mo., assignors to A. B. Chance Company, Centralia, Mo.

Original design application July 8, 1969, Ser. No. 18,108, now Patent No. D. 219,332, dated Dec. 1, 1970. Divided and this application June 24, 1970, Ser. No. 23,628

Term of patent 14 years

Int. Cl. D13—03

U.S. Cl. D8—230

FIG. 1 is a side elevational view of an electrical conductor support showing our new design;

FIG. 2 is a top plan view thereof; and

FIG. 3 is an end elevational view thereof.

This application is a division of design application Ser. No. 18,108 filed July 8, 1969, and entitled Electrical Conductor Support, now Pat. No. D. 219,332.

We claim:

The ornamental design for an electrical conductor support, as shown.
